UNITED STATES PATENT OFFICE.

SINA W. EWER, OF BANGOR, MAINE.

CAP.

1,147,224.

Specification of Letters Patent. Patented July 20, 1915.

Application filed September 21, 1914. Serial No. 862,806.

To all whom it may concern:

Be it known that I, SINA W. EWER, a citizen of the United States, residing at Bangor, in the county of Penobscot and State 5 of Maine, have invented certain new and useful Improvements in Caps, of which the following is a specification.

This invention relates to caps, and more particularly to a cap designed for use by 10 firemen or other persons engaged in a similar occupation, which will protect their eyes from the glare and extreme heat incident to the performance of their duties.

An object of the invention is to provide a 15 cap having a window therein and means to close portions of the window so that the person wearing the cap can adjust the opening of the window to suit varying conditions.

20 Other objects will appear and be better understood by reading the annexed specification in connection with the accompanying drawings, in which:—

Figure 1 is a perspective view of a cap 25 showing the improved vizor attached thereto; Fig. 2 is a plan view of the vizor; and Fig. 3 is a sectional view on the line 3—3 of Fig. 2.

Referring to the drawings by numerals, 30 5 designates a cap body to which is secured in any suitable manner the improved vizor or peak 6. The peak 6 comprises a base portion 7, an intermediate portion 8, and an outer portion 9. The base portion has an opening 10 cut therein, and is further provided with a depression 11 in which is fitted a glass or other transparent material 12. A second opening 13, of the same size and shape as the opening 10 is cut in the outer 35 portion 9, and a third opening 14, slightly larger than the openings 10 and 13 is cut in the intermediate portion 8, a groove being formed by the portion 9 overlapping the portion 8 adjacent the opening therein.

40 Pivoted to the peak as at 15 and adapted to slide in the groove are a pair of shutters 16 and 17, of substantially quadrant shape, and are provided with knobs 18 to facilitate the operation thereof.

45 The opening 14 is of a size and shape to frictionally receive the curved and straight edges of the members 15 and 16 so that when they are in their open position the window will have as great a transparent surface as possible, while, when the same are 50 closed to exclude a direct glare from the

eyes, a portion of the glass will still be open to afford a sight therethrough.

From the foregoing it is thought that the construction and operation of the device 55 will be clearly understood so a further detailed description of the same is dispensed with.

It is wished to have it understood that minor changes in the form and proportion 60 of the invention may be resorted to without departing from the spirit or sacrificing any of the advantages of the same as claimed.

I claim:—

1. In a device of the character described, 70 a cap having a peak attached thereto, a window arranged in said peak, and pivoted means for covering an intermediate portion of said window and allow observance through said window adjacent the ends 75 thereof, substantially as described.

2. In a device of the character described, 80 a cap having a peak attached thereto, a window arranged in said peak, and shutters pivoted upon said peak intermediate the ends of said window whereby they may be moved to cover an intermediate portion of said window and allow observance through said window adjacent the ends thereof, substantially as described. 85

3. In a device of the character described, 90 a cap having a peak attached thereto, a transverse window arranged in said peak, shutter means pivoted upon said peak, the pivot points of said shutter means being spaced from the respective ends of said window, whereby said shutter means may be moved to cover the intermediate portion of said window, and also be moved to allow observance through the intermediate portion 95 of said window, and means for facilitating the movement of said shutters.

4. A cap having a peak with a window 100 therein, said peak being composed of a plurality of sections, said window being disposed between said sections, and a plurality of members pivoted to said peak for closing the opening of the window to any desired degree.

5. A cap having a peak with a window 105 therein, said peak being composed of a plurality of sections, said window being disposed between said sections, a plurality of members pivoted to said peak and slidable upon said window, and means for frictionally holding said members in any desired 110 adjusted position over said window.

6. A cap having a peak with a window therein, said peak comprising a base portion, an intermediate portion, and an outer portion, said window positioned between the 5 base portion and the intermediate portion, a groove formed in said intermediate portion, members pivoted to said peak and adapted to slide in said groove, and knobs

carried by said pivoted members for adjusting the same.

In testimony whereof I affix my signature in presence of two witnesses.

SINA W. EWER.
